UNITED STATES PATENT OFFICE.

EDWARD B. HESS, OF BROOKLYN, NEW YORK, ASSIGNOR TO ROYAL TYPEWRITER COMPANY, OF NEW YORK, N. Y., A CORPORATION OF NEW JERSEY.

LINE-GAGE FOR TYPE-WRITING MACHINES.

1,216,567.

Specification of Letters Patent.

Patented Feb. 20, 1917.

Application filed April 29, 1915, Serial No. 24,675. Renewed January 12, 1917. Serial No. 142,119.

To all whom it may concern:

Be it known that I, EDWARD B. HESS, a citizen of the United States of America, residing in the borough of Brooklyn, county 5 of Kings, and State of New York, have invented a certain new and useful Improved Line-Gage for Type-Writing Machines, of which the following is a specification.

This invention relates to typewriting machines so organized or equipped that, in the absence of the ordinary continuous line gage and scale there is a short line gage and scale plate adjacent the printing point. The invention contemplates an additional or supplemental line gage of improved construction located adjacent the end of the platen.

In another application filed by me, No. 24,674 filed Apr. 29, 1915, I have shown such a general arrangement broadly, and specifically with reference to the supporting of such supplemental line gage above the line of print.

The present invention with respect to the function performed is similar to that described in said application but differs structurally therefrom in that the supplemental line gage is supported below the platen and is extended upwardly to the line of print.

The invention is shown as applied to a 30 Royal "Standard" typewriting machine.

The accompanying drawing shows so much of a typewriter carriage as is deemed desirable for illustration of the invention:

Figure 1 is a cross section through the 35 transversely moving carriage and its shift rail:

Fig. 2, a front elevation of like parts:

Fig. 3, a detail plan view on an enlarged scale of a bracket or support for a supplemental line gage: and

Fig. 4, a front elevation of such gage on an enlarged scale.

1 is the ordinary shift rail; 2, the bottom rail of the transversely moving carriage and 45 3 indicates bearing balls on which the carriage moves. Carried by the shift rail and extending up in front of the platen and opposite the printing point is a card holder that is fixed with reference to the transverse 50 movement of the carriage and comprises a line gage or scale 4 and card holding fingers 5, 5, one on each side of the printing point that extend across the line of print and which are curved to conform more or less 55 to the curvature of the platen. Coöoperating

with these card holding fingers beyond their upper end is a bar 6 running longitudinally of the platen and carried in swinging side arms 7 pivoted at some appropriate point in rear of the platen.

The bar 6 carries paper controlling and feeding rolls 8 that, when in operative position, bear upon the surface of the platen above the ends of the fingers 5. A card holding and guiding apparatus of this general character is disclosed in Letters Patent No. 950,326 dated February 22, 1910, as in my Patent No. 1,105,657 of Aug. 4, 1914, and more detailed description is, therefore, unnecessary. When long lines are to be 70 written upon and especially in filling in long lines upon blanks where printing occurs at separated points in the line, it has been difficult to effect an accurate alinement of the printing line. I have, therefore, provided 75 a supplementary line gage of improved construction located adjacent the end of the platen. 9 is the rear platen feed roll carried upon a shaft 10. 11 is the front feed roll carried upon a shaft 12. Arms 13 extend from the rear feed roll shaft to the cam shaft 14 and the front feed roll shaft is carried in lever arms 15 rocking on or with a shaft 16 extending longitudinally beneath the platen and the rear ends of such 80 lever arms project into engagement with the operating cam shaft 14 by rotation of which the front and rear feed rolls may be moved away from the platen. This is the construction, very well known, that is employed in 85 the Royal Standard typewriter. The plan illustrated of mounting the supplemental line gage is as follows: Said gage comprises a bracket having a front portion 17 and portions 18, 19 extending rearwardly at 90 right angles therefrom. The two arms or portions 18, 19, have co-incident apertures 20, 21 that embrace the shaft 16 and permit longitudinal movement of the bracket thereon. The portion or arm 19 is of greater 100 length than that 18 and is formed at its rear end with a jaw 22 that embraces the cam shaft 14 and holds the bracket against rocking movement on shaft 16. The front face of the bracket has tapped apertures 105 23, 23, to receive clamp bolts 24, 25 that also pass through a line gage carrying plate 26 formed with vertically elongated slots 27 to permit of its adjustment on the bracket. This carrying plate is deflected 110

2

forward tangentially of the platen being to that end bent or angularly formed at the line 28. Its upper end therefore extends forwardly obliquely to about a vertical plane 5 in which the front face of the platen lies and is formed with curled tongues 29, 29, that receive a hinge pin 30 that also passes through like curled bearings formed on the gage plate 31. The gage supporting plate 26 is slit in parallel lines at its central portion forming a spring tongue that passes upwardly back of the gage plate 31 and on the latter is a downwardly projecting tongue 33 turned up and overlying the spring tongue 32. The gage plate 31 may therefore be swung upon the hinge joint described and held in either upright or depressed position by the reaction of the spring tongue. When in elevated position, its upper edge, 20 which may, if desired, be inscribed with a scale, lies at the line of print. The screw bolt 25 is extended well to the front as seen in Fig. 1, and will contact with the lower part of card holding finger 5, causing the 25 gage to slide on shaft 16 and so prevent the type bars from striking the gage. The supplemental gage device as a whole is capable of longitudinal movement on shafts 16 and 14. In the traverse of the platen, should 30 the supplemental gage 31, when down, come in contact with the card guide finger 5 the gage will slip upon the shaft 16 to the outer end of the platen so that all, or substantially all, of the printing face of the platen 35 will be available for printing purposes.

A side line gage, similar in all respects to that described applied to the right hand end of the platen, may be applied to the left hand end of the platen, as shown at Fig. 2, 40 with corresponding parts similarly indicated. This gage 31, as here shown, is moved down when the margin part of a wide sheet is being written on, the center gage 4 then being used for adjusting the 45 sheet as shown in Fig. 2. At other times the three gages may be used, or the left hand gage may be used to adjust a wide sheet when writing is being done on the right hand portion of the sheet.

60 I claim:

1. Line gage devices for a typewriting machine comprising a short fixed line gage located at the printing point and a supplemental line gage located adjacent one end

of the platen mounted to move with the 55 platen under the line of print and adjustable in its mounting toward and from the end of the platen and relatively to the fixed gage.

2. Line gage devices for a typewriting machine, comprising a short fixed line gage 60 located at the printing point and a supplemental line gage located adjacent one end of the platen mounted to move with the platen below the line of print and adjustable 65 in its mounting vertically with reference to the line of print and horizontally toward and from the end of the platen.

3. Line gage devices for a typewriting machine, comprising a short fixed line gage 70 located at the printing point and a supplemental line gage mounted beneath the line of print and located adjacent one end of the platen and comprising a part mounted for adjustment toward and from the end of the 75 platen, a part vertically adjustable relatively to the line of print, and a third part movable transversely toward and from the platen.

4. The combination of a platen, its carriage, a rod beneath the platen forming part of the carriage frame, a bracket attached to said rod, a vertically adjustable plate mounted on said bracket and a line gage plate hinged to said vertically adjustable 85 plate.

5. The combination of the platen, its carriage, the paper feed rolls, a rod beneath the platen in the carriage frame supporting said paper feed rolls, a cam shaft for raising and lowering said rolls, a bracket supported by said rod and having a part engaging said cam shaft, and a line gage attached to said bracket. 90

6. The combination with a platen, its carriage, a rod in the carriage beneath the platen, a bracket free to slide on said rod in a line parallel with the axis of the platen, and a line gage carried by said bracket and having an upper part mounted to move toward and from the platen. 95 100

In testimony whereof, I have hereunto subscribed my name.

EDWARD B. HESS.
